SIMULATED BOWLING GAME APPARATUS

Lyndon A. Durant and Melvin J. Binks, Chicago,
Ill., assignors to Republic Patent Corporation,
Chicago, Ill., a corporation of Illinois

Application April 22, 1950, Serial No. 157,551

6 Claims. (Cl. 273—126)

1

This invention relates to simulated bowling game apparatus in which a puck or other game piece is manually propelled over a playing field for contact with one or more switches in the power circuit of mechanism operable to pivot simulated bowling pins from a vertical display position to a horizontal position above the playing field.

An object of the invention is to provide an apparatus of this character which will afford the maximum amusement.

Another and equally important object of the invention is the provision of an arrangement for supporting the simulated bowling pins in a standard formation and for moving one or more of such pins from such supported position to simulate the knocking down of one or more pins by the game playing puck or other playing piece.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary perspective view, partly in section illustrating the invention;

Fig. 2 is a top plan view of the bowling pin supporting panel embodied in the invention;

Fig. 3 is a sectional detail view taken on line 3—3 of Fig. 2;

Fig. 4 is a view of the supporting panel shown in Fig. 2 but illustrating the underside thereof;

Fig. 5 is a perspective view of a combination latch and support for a simulated bowling pin embodied in the invention;

Fig. 6 is a side view of the same taken substantially on line 6—6 of Fig. 2;

Fig. 7 is a view similar to Fig. 6 but showing the simulated bowling pin in a raised position;

Fig. 8 is a fragmentary plan view of the switch-carrying portion of the playing field embodied in the invention;

Fig. 9 is a fragmentary sectional detail view taken substantially on line 9—9 of Fig. 8; and

Fig. 10 is a schematic wiring diagram embodied in the invention.

The several objects of our invention are accomplished by the preferred form of construction shown in the accompanying drawings wherein there is illustrated a cabinet 15.

Within this cabinet 15 is an elongated board providing a playing field 16 and over which a puck or other game piece is adapted to be pro-

2

pelled for contact with one or more switches. These switches are arranged on the playing field 16 into two groups, one indicated at 17 and referred to as the "strike" switches arranged within an indicated strike zone 18, and the other group indicated at 19 and known as the "spare" switches and arranged outside of the strike zone 18.

Each switch comprises, as illustrated in Fig. 10, 9, cooperating switch leaves 20 of the spring type adapted to be closed by an actuating lever 21 pivoted at 22 and having a portion 23 extending upwardly through a slot 24 formed in the playing field.

15 The portion 23 has a pin 25 which bears upon the upper of the spring leaves 20. The arrangement is such that when a puck passes over the portion 23, the upper of the switch leaves 20 will by reason of its engagement with the pin

20 25 be flexed into contact with the lower of the switch leaves 20 upon pivotal movement of the actuating arm 21 by engagement with the puck. These switches control an electric circuit to electromagnetic elements hereinafter more fully referred to.

Above the switch bearing portion of the playing field 16 and in spaced relation with respect thereto is a transparent plate 26 which constitutes the bottom wall of a cabinet 27 extending upwardly from the cabinet 15.

This upright cabinet 27 comprises a transparent front wall 28 and a top wall 29. Beneath the top wall 29 and in spaced relation with respect thereto is a supporting panel 30. The top wall 29 is connected to this supporting panel 30 and to the side walls of the cabinet 27 by means of suitable screws 32.

From this panel 30 is supported a plurality of simulated bowling pins 33. Each pin 33 comprises a plastic body having attachment as at 34 to the end portion of a supporting rod 35. This supporting rod 35 is formed to provide an intermediate portion 36 which is pivotally connected to the portion 37 of a mounting bracket 38.

45 In the panel 30 is formed a slot 39 into which this portion 37 of the mounting bracket 38 is positioned. The rod 35 outwardly of the intermediate portion 36 is bent to provide a portion 40 extending in parallel spaced relation with respect to the intermediate portion 36 to provide a bar portion cooperating with a latch 41 provided by the armature 42 of an electromagnetic coil 43. This armature 41 is yieldably held in position for latched engagement with the bar 50 44 by a spring 44. The coil 43 is carried by an arm

45 provided by the bracket 38. The bracket 38 is attached to the panel in the position shown in Fig. 6 by means of screws 46.

To the upper end portion of the rod 35 there is attached as at 48 one end portion of a spring 49, the opposite end of the spring 49 being attached to the panel 30 as at 50. When the rod 35 with its simulated pin 33 is disposed in a vertical position with the bar 40 in latched position with respect to the latch 41 the spring 49 is placed under tension so that when the coil 43 is energized to pivot the armature 42 therefrom to remove the latch 41 from engagement with the bar 40 this spring will serve as a motive power to pivot the rod 35 and its simulated pin to a horizontal position beneath the panel 30 as shown in Fig. 7. The simulated pin 33 and the rod 35 are maintained in this position by the spring 49.

Each of the simulated bowling pins is supported from the panel 30 in the manner illustrated in Figs. 5 and 6 and each is moved from vertical position as shown in Fig. 1 to the horizontal position as shown in Fig. 7 by its respective spring 49 when the individual rods 35 are released from latched engagement with their respective latches 41 by the electromagnetic coils 43 controlling the operation of such latches.

In order to prevent each of the pins 33 from striking against the underside of the panel 30 when pivoted to such position under the action of the spring 49, we provide a felt bumper disk 50'. This disk 50' is carried by a plate 51 secured as at 52 to the underside of the panel and the disk is arranged to be engaged by the rod 35.

Means is provided for pivoting the simulated pins 33 from the horizontal elongated position shown in Fig. 7 back to the vertical position shown in Fig. 1. This means comprises a motor 53 connected as at 54 to the top side of the panel 30. On the shaft 56 of the motor 53 is a disk 60. Eccentrically connected to this disk 60 as at 61 is a link 62. A pin 63 extends downwardly from the outer end portion of this link 62 through a slot 64 formed in the panel 30 for connection with an arm 65 of a reset bar 66 slidably supported by suitable brackets 67' on the under-surface of the panel 30 as shown in Fig. 4.

This reset bar 66 comprises spaced arms 67 which are adapted to engage the bent portion 68 of each of the rods 35 so that when the reset bar 66 by operation of the motor 53 is moved relative to the panel 30 in the direction toward the bent portions 68 of the rods 35, the arms 67 will engage such bent portions 68 and pivot the rods 35 to the position shown in Fig. 1 with the bars 40 latched against the action of the springs 49 by the latch plates 41.

Connected to the pin 63 is one end of a spring 69, the opposite end of the spring being connected as at 70 to one of the arms 45 of the bracket 38.

The arrangement is such that when the reset bar 66 is in its retracted position as shown in Fig. 4 the spring 69 will be under tension so that as soon as the pivot point 61 between the disk 60 and the link 62 has crossed the long axis of the shaft 56 this spring will work with the motor and thereby assist the motor in its operation of moving the reset bar 66 in the direction to pivot the rods 35 and their simulated pins to the vertical position shown in Fig. 1.

The motor 53 may be connected in circuit with a power source 71 controlled by a switch 72 in turn controlled by a conventional coin slide 73'.

The present object of our invention is to in-

corporate switches 17 in the strike zone in an electric circuit whereby when any one of such switches 17 is closed by the puck all of the simulated pins 33 will be released for pivotal movement from a vertical position to a horizontal position beneath the panel 30 thereby to simulate the accomplishment of a strike. Any approved circuit to accomplish this object may be provided. We have shown, however, a suggested circuit in Fig. 10.

In this circuit, corresponding sides of the switches 17 are connected by a conductor 73 to one side of a power source 74. The other side of this power source by a conductor 75 is connected to one side of a motor 76. The opposite side of this motor 76 by a conductor 77 is connected to the opposite side of the switches 17. On the shaft 78 of this motor is a cam disk 79 which controls the closing of a switch 80. One side of this switch 80 by a conductor 81 is connected to the conductor 75. The other side of this switch 80 by a conductor 82 is connected to the conductor 77. The arrangement is such that when any one of the switches 17 is closed by the puck the motor 76 will be energized and the initial movement of this motor will rotate the cam disk 79 to close the switch 80 which switch 80 will remain closed until the cam disk 79 has made one complete cycle of rotation. On the shaft 78 is a wiper finger 83 connected by a conductor 84 to the conductor 75. This wiper finger 83 is adapted to successively engage contacts 85 connected to corresponding sides of the coils 43.

The opposite corresponding sides of the coils 43 by a conductor 86 is connected to the conductors 75 and 81. The arrangement is such that when the wiper finger 83 successively engages the contacts 85 the coils 43 will be successively energized to pivot their respective armatures 42 to release the latch plates 41 from engagement with the bars 40 whereby to permit the rods 35 and their simulated pins to be pivoted to the position shown in Fig. 7 under the action of the springs 49.

It is also the object of our simulated bowling game to energize certain of the coils 43 upon the independent closing of the switches 19 which switches as before stated are termed the "spare" switches. Each of these switches controls the energization of a particular coil of the coils 43. For this purpose any suitable circuit may be provided. In Fig. 10 a suggested circuit is disclosed. In that circuit, we have shown only two of the switches 19 for purpose of illustration. One side of each switch is connected to the one side of its respective coil 43 by a conductor 81. The other side of each switch is connected by a conductor 83 to one side of the power source 74. When one of the switches 19 is closed a circuit will be established through conductor 83, its respective coil 43, conductors 86, 81 and 75. The energization of such coil 43 will release the simulated pin 33 of that particular unit for pivotal movement from the position shown in Fig. 1 to the position shown in Fig. 7.

By the foregoing arrangement we have provided a simple, compact and effective arrangement for automatically pivoting the simulated pins from a vertical display position to a horizontal position simulating the accomplishment of a strike or a spare.

While we have illustrated and described the preferred form of construction for carrying our invention into effect, this is capable of variation and modification without departing from the

spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. A simulated bowling amusement game apparatus comprising a supporting structure including a playing field and a horizontally arranged panel disposed in confronting spaced relation with respect to the field, a plurality of simulated bowling pins, means providing pivotal connection between the panel and said pins, means carried by the panel and connected to said pin connecting means for pivoting the said pins from a position vertically with respect to said panel to a position horizontally with respect thereto, electromagnetic means including latch structures for latching said pins in said vertical position, spring means connected to said panel and to said pin connecting means for pivoting said pins to said vertical position when said pins are unlatched from said latched structures, and a power circuit for said electromagnetic means including switches each having a playing piece engaging element arranged on the playing field.

2. A simulated bowling amusement game apparatus comprising a supporting structure including a playing field and a horizontally arranged panel disposed in confronting spaced relation with respect to the field, a plurality of simulated bowling pins, means providing pivotal connection between the panel and said pins, means carried by the panel and connected to said pin connecting means for pivoting the said pins from a position vertically with respect to said panel to a position horizontally with respect thereto, electromagnetic means including latch structures for latching said pins in said vertical position, spring means connected to said panel and to said pin connecting means for pivoting said pins to said vertical position when said pins are unlatched from said latched structures, and a power circuit for said electromagnetic means including switches each having a playing piece engaging element arranged on the playing field, and means engageable with said pin connecting means for moving said pins from said horizontal position to said vertical position with respect to said panel.

3. A simulated bowling amusement game apparatus comprising a supporting structure including a playing field and a horizontally arranged panel disposed in confronting spaced relation with respect to the field, a plurality of simulated bowling pins, means providing pivotal connection between the panel and said pins, means carried by the panel and connected to said pin connecting means for pivoting the said pins from a position vertically with respect to said panel to a position horizontally with respect thereto, electromagnetic means including latch structures for latching said pins in said vertical position, spring means connected to said panel and to said pin connecting means for pivoting said pins to said vertical position when said pins are unlatched from said latched structures, and a power circuit for said electromagnetic means including switches each having a playing piece engaging element arranged on the playing field, and means engageable with said pin connecting means for moving said pins from said horizontal position to said vertical position with respect to

said panel, said last named means including an electric motor and a power spring cooperating with said motor.

4. A simulated bowling amusement game apparatus comprising a supporting structure including a playing field and a horizontally arranged panel disposed in confronting spaced relation with respect to the field, a plurality of simulated bowling pins, means providing pivotal connection between the panel and said pins, means carried by the panel and connected to said pin connecting means for pivoting the said pins from a position vertically with respect to said panel to a position horizontally with respect thereto, electromagnetic means including latch structures for latching said pins in said vertical position, spring means connected to said panel and to said pin connecting means for pivoting said pins to said vertical position when said pins are unlatched from said latch structures, and a power circuit for said electromagnetic means including switches each having a playing piece engaging element arranged on the playing field, and means engageable with said pin connecting means.

5. A simulated bowling amusement game apparatus comprising a supporting structure including a playing field and a horizontally arranged panel disposed in confronting spaced relation with respect to the field, a plurality of simulated bowling pins, means providing pivotal connection between the panel and said pins, means carried by the panel and connected to said pin connecting means for pivoting the said pins from a position vertically with respect to said panel to a position horizontally with respect thereto, electromagnetic means including latch structures for latching said pins in said vertical position, spring means connected to said panel and to said pin connecting means for pivoting said pins to said vertical position when said pins are unlatched from said latch structures, and a power circuit for said electromagnetic means including switches each having a playing piece engaging element arranged on the playing field, said switch elements being arranged in groups with one group controlling the power circuit to less than all of said electromagnetic means and another group controlling the power circuit to all of said electromagnetic means.

6. A simulated bowling amusement game apparatus comprising a supporting structure including a playing field and a horizontally arranged panel disposed in confronting spaced relation with respect to the field, a plurality of simulated bowling pins, means providing pivotal connection between the panel and said pins, means carried by the panel and connected to said pin connecting means for pivoting the said pins from a position vertically with respect to said panel to a position horizontally with respect thereto, electromagnetic means including latch structures for latching said pins in said vertical position, spring means connected to said panel and to said pin connecting means for pivoting said pins to said vertical position when said pins are unlatched from said latch structures, and a power circuit for said electromagnetic means including switches each having a playing piece engaging element arranged on the playing field, said switch elements being arranged in groups

with one group controlling the power circuit to less than all of said electromagnetic means and another group controlling the power circuit to all of said electromagnetic means, said last named means including a reset bar slidably carried by the panel and engageable with said pin connecting means.
